(57) **CLAIM**

The ornamental design for a combined case and band for smart watch, as shown and described.

DESCRIPTION

FIG. 1 is a front perspective view of a combined case and band for smart watch showing my new design; FIG. 2 is another front perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a rear perspective view thereof; and, FIG. 10 is another rear perspective view thereof. The broken lines in the drawing figures depict portions of the combined case and band for smart watch that form no part of the claimed design.

1 Claim, 10 Drawing Sheets
